UNITED STATES PATENT OFFICE.

JOHN W. HEIGH, OF ROCHESTER, NEW YORK.

CHUCK FOR LATHES AND THE LIKE.

1,417,169.

Specification of Letters Patent. Patented May 23, 1922.

Application filed December 16, 1920. Serial No. 431,187.

To all whom it may concern:

Be it known that I, JOHN W. HEIGH, a citizen of the United States of America, residing at Rochester, in the county of Monroe and State of New York, have invented certain new and useful Improvements in Chucks for Lathes and the like, of which the following is a specification.

My invention relates to chucks for lathes and the like, and has for its object to provide a work holding chuck of the type adapted to be detachably mounted on the end of a spindle.

A more particular object of the invention is to afford a simple and practical mechanism, of such character that the operator can readily position or remove a piece of work, the work being held tightly and rigidly, when engaged by the collet.

An additional object of the improvement is to make it possible for the operator to attach a piece of work quickly and conveniently, through operating means that is in immediate proximity to the point where the work is held.

The invention is also intended to accomplish certain other purposes, and includes various improvements, as will be fully understood from the following description, considered in conjunction with the accompanying drawings, while the novel features of my invention are pointed out in the claims following the description.

In the drawings:

Figure 1 is an elevation of the work holding end of a chuck, constructed in accordance with a preferred embodiment of my invention, and with a portion of the housing removed.

Figure 2 is a side elevation of the portion of the housing adapted to be attached to the parts illustrated in Figure 1.

Figure 3 is a longitudinal sectional view on line 3—3 of Figure 1, and showing the collet in position for clamping the work.

Figure 4 is a longitudinal sectional view on line 4—4 of Figure 1, and showing the collet in position for releasing the work.

Figure 5 is an end elevation of the chuck, looking at the work retaining end.

Figure 6 is an end elevation of the chuck, looking at the spindle engaging end.

Figure 7 is an enlarged side elevation of

the operating mechanism, partly broken away, and with parts removed to illustrate the reversible dog positioned for tightening the collet.

Figure 8 is a similar view, with parts broken away, illustrating the reversible dog positioned for loosening the collet.

Figure 9 is a plan view of the reversible dog.

Figure 10 is a detail sectional view on line 10—10 of Figure 7, and

Figure 11 is a sectional view on line 11—11 of Figure 4.

In general, the chuck of my invention embodies a collet slidable in a housing, and having connected therewith an actuating member, preferably in the form of a collar in threaded engagement with the collet. By turning the collar referred to, the collet is caused to slide one way or the other, and its slidable movement is reversed when the actuating collar is turned in the reverse direction. The actuating member or collar is controlled by oscillatory operating means, which preferably includes a frame carrying a device for engagement with the actuating collar and acting when adjusted, to move the collar in either direction of rotation. This may be brought about by a pivoted dog that is reversible so as to cooperate in either one of two positions with teeth on the actuating collar, and the frame carrying the dog is preferably provided with a manipulating hand wheel.

The purposes of the invention can be carried out in various ways, and the mechanism herein described is to be understood as merely one example of various practical embodiments. In the structure illustrated, 1 and 2 designate complementary parts of a housing which are held together by threaded pins 3, the entire assembly being adapted for support on the end of a spindle by means of the threaded portion 4 on the housing section 1. In order to afford an accurate fit between sections 1 and 2, section 1 is provided with recesses 5, Figures 1 and 2, formed in the sides of extensions 6, and adapted to receive cooperating locking lugs or pins 7.

8 designates the collet arranged within the housing and adapted for sliding movement, either to the position shown in Figure

3 for clamping the work α , or to the position shown in Figure 4 for releasing the work, and I will now describe the mechanism by which this sliding movement of the 5 collet is accomplished.

9 designates the collet actuating member 10 preferably consisting of a collar with an interior threaded portion 10, engaging a threaded end on the collet, so that when the actuating member 9 is rotated in one direction or the other, it produces a corresponding sliding movement of the collet. The latter, when drawn inwardly to the position shown 15 in Figure 3, is clamped about the work by reason of the engagement of projections 11 with the inclined seat 12, and when the collet is moved outwardly as in Figure 4, its split ends are freed and the work released.

The actuating member 9 is adapted to be 20 controlled by oscillatory operating means, provided with a manually adjustable device for fixing the direction of rotation of the actuating member when the operating means is oscillated. To accomplish this, the actuating collar 9 is provided with a series of 25 teeth 13, and the operating means includes a frame comprising a pair of plates 14 and 15, which at their central portions are spaced from each other and located on opposite 30 sides of the teeth 13.

16 designates a bearing or pin supported between the plates 14 and 15, and pivoted on the pin 16 is a manually reversible device or dog. The latter includes two operating portions 17 and 18 arranged on opposite sides of the pivotal point, and a manipulating finger portion 20, which extends through an opening 21 in the housing and is accessible from the exterior, in order to 40 adjust the position of the dog. When the dog is positioned as shown in Figure 7, by oscillating the operating means or frame, the collet is tightened, and upon reversing the position of the dog, as illustrated in 45 Figure 8, oscillation of the operating means serves to loosen the collet. The reversible dog cooperates with the toothed actuating collar 9 after the fashion of a ratchet pawl, being drawn over the teeth during its return 50 movement, and having engagement with one of the teeth during its forward movement, and suitable mechanism is provided for holding the pawl in the selected position of adjustment.

To this end, each operating portion of the 55 dog is provided with curved recesses or pockets 22 located at its four edges, or in other words, on both sides, and both inwardly and outwardly of the operating portion, 60 and the recesses on each side are arranged in juxtaposition to each other for a purpose that will appear presently.

Attached to the plates 14 and 15 are cups 23, constituting retainers for balls 24, the 65 latter being actuated by springs 25 and co-

operating with the recesses 22 as shown in Figure 10. By disposing the side recesses in juxtaposition to one another, the balls 24 snap instantly from one recess into the other, and thus assist in the manual operation of 70 changing the position of the dog. It will be understood that to adjust the dog from one position to another, sufficient pressure must be applied to the finger piece 20 to overcome the resistance of the springs 25, and it will 75 be observed that the dog is held in either position of adjustment by the simultaneous engagement of balls with the inner pockets or recesses on one operating portion of the dog and the outer pockets on the other operating portion of the dog, thus imparting a 80 maximum locking effect, and preventing any accidental displacement of the dog.

The operating means is preferably manipulated by a hand wheel or equivalent 85 member surrounding the chuck, and to this end, the plates 14 and 15 have outwardly projecting offset portions or extensions 26 which are located adjacent to one another and have attached thereto a hand wheel 27. 90

It is essential that the actuating collet 9 be held firmly in adjusted position so as to maintain a tight grip on the work, and this is accomplished in the following manner. Fixed within a recess in the housing section 95 2 is a retaining collar 28 having openings or pockets therein. Mounted in the pockets 29 are spring actuated balls 30 which engage corresponding recesses in the side of the actuating collar 9, as shown in Figures 3 and 100 4. This imparts sufficient frictional locking effect upon the actuating collar 9 to prevent its accidental movement or slipping. The retainer 28 also carries a key 31 which engages a groove in the collet 8 to prevent 105 turning movement of the latter within the housing.

In operating the device, the entire unit is first securely fixed on a supporting spindle by threading the portion 4 thereon. With 110 the collet released, as shown in Figure 4, a work piece α is inserted, and the finger 20 of the reversible dog adjusted as shown in Figure 7.

Then by moving the hand wheel 27 back 115 and forth, the amount of such movement being determined by the space between the projecting portions 6, see Figure 1, the actuating collar is turned in the direction of the arrow, see Figure 7, thereby sliding the 120 collet inwardly from its position of Figure 4, until it reaches the position shown in Figure 3. To release the work, the finger piece 20 is shifted to the position shown in Figure 8, and then by moving the hand wheel 27 back and forth, the actuating collar 9 is caused to travel in the direction shown by the arrow in Figure 8, thereby sliding the 125 collet 8 outwardly to the position shown in Figure 4. 130

While I have described the invention with reference to a particular mechanism, it is not limited to the details shown, but may be modified without departing from the fundamental purposes set forth, and as defined in the following claims.

I claim:

1. A chuck comprising a collet, a rotary actuating member cooperating with the collet, and operating means controlling said actuating member and including an oscillatory hand wheel surrounding the chuck and having an alternating grip and release engagement with said actuating member.
- 15 2. A chuck comprising a housing, a collet slidably arranged in the housing and held against rotation, a rotary actuating member cooperating with the collet for sliding it back and forth, and operating means for the actuating member including an oscillatory hand wheel surrounding the chuck and having an alternating grip and release engagement with said actuating member.
- 25 3. A chuck comprising a collet, a rotary actuating member cooperating with the collet, and operating means surrounding the chuck and acting, when oscillated, to cause a rotary movement of the actuating member in one direction.
- 30 4. A chuck comprising a collet, a rotary actuating member cooperating with the collet, and operating means surrounding the chuck and acting, when oscillated, to cause a rotation of the actuating member in one direction, the operating means including a manually adjustable device which is posi-

tionable to determine the direction of rotation of the actuating member.

5. A chuck comprising a housing, a collet slidable in the housing, a rotary actuating member cooperating with the collet and provided with a series of teeth, and oscillatory operating means including a reversible dog cooperating with said teeth so as to move the actuating member in either direction.

6. A chuck comprising a housing, a collet slidable in the housing, a rotary actuating member cooperating with the collet and provided with a series of teeth, oscillatory operating means including a reversible dog cooperating with said teeth so as to move the actuating member in either direction, and frictional locking means for holding the dog in adjusted position.

7. A chuck comprising a housing, a collet slidable within the housing, a rotary actuating member cooperating with the collet and having a series of teeth thereon, oscillatory operating means including a pair of plates located on opposite sides of the aforementioned teeth, a manually reversible dog journaled between said plates so as to cooperate with said teeth in opposite positions for moving the actuating member in one direction or the other, said plates having extensions arranged adjacent to one another at their outer ends and a hand wheel connected to said outer ends of the plates for manipulating the operating means.

In witness whereof, I have hereunto signed my name.

JOHN W. HEIGH.
